UNITED STATES PATENT OFFICE.

REGINALD HEBER EARLE, OF ST. JOHN, NEWFOUNDLAND.

SIGNAL-BOMB.

SPECIFICATION forming part of Letters Patent No. 399,854, dated March 19, 1889.

Application filed October 17, 1888. Serial No. 288,312. (No model.)

To all whom it may concern:

Be it known that I, REGINALD HEBER EARLE, of St. John, Newfoundland, have invented a new and Improved Signal-Bomb, of which the following is a full, clear, and exact description.

This invention relates to marine signals, the object of the invention being to provide a signal-bomb which will not be affected by dampness, which may be ignited irrespective of the state of the weather, and which shall be so constructed that in exploding it will send aloft a heavy volume of flame and smoke, an explosive giving a heavy detonation being preferably employed.

Reference is to be had to the accompanying drawings, forming a part of this specification, in which similar figures and letters of reference indicate corresponding parts in all the views.

Figure 1 is a central sectional elevation of my improved signaling-bomb. Fig. 2 is a central sectional elevation of a modified construction. Fig. 3 is a plan view of the construction shown in Fig. 1, the top disk or plate, however, being removed. Fig. 4 is a sectional plan view taken on line *x x* of Fig. 2. Fig. 5 is a side view of the screw-cap, and Fig. 6 is an end view of said cap.

In constructing such a bomb as the one forming the subject-matter of this application, I provide an outer vessel, 10, which is preferably cylindrical, but which might be made of any desired form. Within the vessel 10 there is placed a vessel, 11, which rests upon the bottom of the vessel 10, and in connection with the vessel 11, I arrange tubes 12 and 13, said tubes extending through a disk, 14, which is tightly connected to the vessel 10, thus forming an air and water tight compartment, A. The tube 12 extends downward within the vessel 11, the walls of this extending section of the tube being perforated, as shown at *a*. Above the disk 14 there is arranged a removable disk, 15, formed with an upwardly-extending and threaded nipple, 16, which nipple serves as the support for the fuse 17, this fuse being carried downward within the tube 12, as is clearly shown in Fig. 1.

In preparing the bomb for use the vessel 11 is filled with any proper explosive, the material

being introduced through the tube 13. After the vessel 11 has been filled with the explosive, a small amount of the explosive is introduced through the tube 12, the lower end of the fuse 17 resting upon the explosive so placed within the tube 12. To the upper end of the fuse there is attached an instantaneous fuse-igniter, *b*, which extends slightly above the upper end of the nipple 16. After the fuse 17 has been properly prepared and placed, the nipple 16 is covered by a cap, 20, that is internally threaded to engage the thread of the nipple. In the outer face of the cap 20 there are formed one or more concave grooves, *c*, the exposed face of the cap within these grooves being roughened. Such, in short, is my improved form of bomb.

In using the bomb, the cap 20 is removed and any one of its roughened faces is drawn against the igniter above the upper end of the fuse. The bomb is then thrown overboard, and upon striking the water will float and assume a position that is substantially vertical, care being taken in the filling of the bomb to secure sufficient weight within or below the vessel 11 to hold the vessel 10 in a vertical position. When the explosion takes place, the water in which the bomb is immersed acts as a confining medium, and the products of combustion will rise vertically to a great height, so that they may be seen for many miles around.

In selecting the explosive it is desirable that an explosive which will produce a heavy smoke and a great noise be employed. In certain cases it might be well to provide the bomb above described with a rocket, and to this end I would in some cases attach a cup, 23, to the vessel 11, the tubes 12 and 13 being in this case removed to one side, as shown in Fig. 4. The cup 23 serves as the support for the lower end of a rocket, 30, the upper end of the rocket being held by a disk, 31, that is arranged below the disk 14, the disk 31 being centrally apertured to provide for the passage of the rocket, as is clearly shown in Fig. 2. With this construction the rocket would be ignited by the explosive within the vessel 11.

The advantages of such a bomb as the one above described are great and varied, inasmuch as the signal is of a nature such that it

would be understood by persons of every nationality, and the construction of the bomb is such that it might be used where other signaling appliances could not be employed.

5 Having thus described my invention, I claim as new and desire to secure by Letters Patent—

1. A signal-bomb formed with an air-chamber, a chamber adapted to receive an explosive material and provided with a tube which leads from the explosive-receiving chamber through the air-chamber, said tube being adapted to receive a fuse, a disk arranged above the upper end of the tube, a nipple extending upward from the disk, and a cap formed with a roughened surface adapted to fit upon the nipple, substantially as described.

15 2. In a bomb, the combination, with a vessel, 10, of a vessel, 11, arranged therein, a disk, 14, also arranged within the vessel 10 and above the vessel 11, tubes 12 and 13, leading from the vessel 11 upward through the vessel 10 and through the disk 14, a disk, 15, arranged

above the disk 14, a nipple formed upon said disk, and a roughened-faced cap arranged in connection with the nipple, substantially as described.

3. In a bomb, the combination, with a vessel formed with an air-chamber and provided with a chamber adapted to receive an explosive below said air-chamber, of a rocket arranged within the air-chamber and a fuse-tube leading downward through the air-chamber to the explosive-chamber, substantially as described.

30 4. The combination, with a vessel provided with a nipple into which the fuse is adapted to project, of a cap fitting on the nipple and having a roughened surface, substantially as and for the purpose set forth.

REGINALD HEBER EARLE.
